UNITED STATES PATENT OFFICE

158,835

FOOD MIXER

William F. Bisley, Oak Park, Ill., assignor to Dor-meyer Corporation, Chicago, Ill., a corporation of Illinois

Application July 5, 1947, Serial No. 140,118

Term of patent 7 years

(Cl. D44—1)

To all whom it may concern:

Be it known that I, William F. Bisley, a citizen of the United States, residing at 818 North Ridge-land Avenue, in the village of Oak Park, county of Cook, and State of Illinois, have invented a new, original, and ornamental Design for a Food Mixer, of which the following is a specification, reference being had to the accompanying drawing, forming a part thereof:

Fig. 1 is a top plan view of a food mixer showing my new design;

Fig. 2 is a side elevational view thereof;

Fig. 3 is a rear elevational view thereof; and

Fig. 4 is a front elevational view thereof.

The dominant feature of my design resides in the food mixer shown in full lines.

I claim:

The ornamental design for a food mixer, as shown and described.

WILLIAM F. BISLEY.
